ADALINE EMERSON

By her Attorney
Morris Bernstein

UNITED STATES PATENT OFFICE.

ADALINE EMERSON, OF NEW YORK, N. Y.

LADY'S GARMENT.

1,402,404.

Specification of Letters Patent.

Patented Jan. 3, 1922.

Application filed May 16, 1919. Serial No. 297,462.

To all whom it may concern:

Be it known that ADALINE EMERSON, of San Francisco, California, a citizen of the United States and residing in the city of 5 New York, in the county of New York and State of New York, has invented certain new and useful Improvements in Ladies' Garments, of which the following is a specification.

10 This invention relates to ladies' undergarments and is directed particularly to providing a novel and advantageous construction of ladies' drawers.

One object of my invention is to provide 15 a pair of ladies' drawers which may avoid the necessity of drawing the garment down over the head or up from the feet of the wearer.

Another object of this invention is to provide 20 a pair of ladies' drawers which may be donned by the wearer with unusual ease and facility and also be comfortable to the wearer.

A further object of my invention is to 25 provide a pair of drawers of this character in which the leg portions may be opened flat leaving one continuous smooth piece of fabric for laundering purposes.

My invention is of particular advantage 30 in that it provides a very loose and comfortable drawer construction and has special application as an undergarment to be worn when horse back riding or dancing.

Other objects and advantages of this invention will appear from the detailed description and the features of novelty will be particularly pointed out in the claims.

In the drawing accompanying this specification and forming a material part 40 thereof,

Fig. 1 is a view showing the undergarment, an embodiment of my invention, as it appears on the wearer.

Fig. 2 is a vertical elevation of a pair of 45 drawers constructed according to my invention, showing the garment in folded position ready to be buttoned at the side.

Fig. 3 is a similar view to Fig. 2 showing the garment in unfolded position as presenting one continuous smooth surface for laundering.

Fig. 4 is a view looking up of the garment as it appears on the wearer.

Referring in detail to the drawing, the 55 pair of drawers, the embodiment of my invention there shown, is seen to be formed

from two pieces of material stitched together as at 10, cut to provide a waist portion 11 and two symmetrically disposed portions 12 and 13 extending therefrom adapted to form the leg portions of the drawers. The waist portion 11 is of sufficient width to comfortably and yet securely fit around the wearer's waist, while the leg portions 12, 13 extend out from said waist portion gradually widening in apron like fashion so as to accommodate comfortably the legs of the wearer as will be readily understood. The piece 12, adapted to form the back portion is made longer than the front portion 13 so 70 as to allow for a crotch portion as will be readily understood. Of course, the portions 11, 12 and 13 may be cut from one piece of material instead of two as shown in the drawing and described.

75 One of the leg portions such as the back portion 12 is provided with a connecting tab 14 at the center near the bottom which may be conveniently buttoned beneath the crotch to the other portion 12 to close the 80 front and back portions in drawer fashion as will be readily understood. Along the free edge of one of these portions such as the front portion 13 I provide fastening means such as buttons, hooks or snaps 15 85 whereby the garment may be buttoned around the body to the other portion 12 which is provided with corresponding sockets, eyes or the like receiving means for the fastening or buttoning means 15. By 90 making the garment open at the side it is readily accessible for adjustment on the body of the wearer and also gives a much neater appearance. In order to allow for an adjustment in the size of the waist an 95 elastic 17 may be provided in the waist portion.

If desired, a camisole portion 18 may be provided together with straps 19 extending therefrom or other suitable means for securing the garment on the body of the wearer. This camisole portion may be made in the form of a separate piece stitched to the portions 12 and 13 or may be continuous therewith, and provided at the side 100 105 with fastening means 15' and 16'.

Of course, the garment may be suitably finished as with a ruffle 20 running from the waist line at the side around the bottom up to the waist line on the opposite side. This 110 ruffle may be attached in any suitable manner such as by hemstitching or machine

stitching or ordinary hand sewing. To further provide for neatness in finish the edge of the ruffle may be picot finished or provided with an ordinary hem or lace edging.

5 The cut is preferably in the form of an apron and when the two parts are folded over as in Fig. 2, the garment has the appearance of an apron and as will be readily understood may be opened out into one 10 piece and ironed as any ordinary apron. In the use of the garment, the wearer has only to button the two portions 12 and 13 about the body at the side and then to adjust the flap 14.

15 This garment is of particular advantage to persons of poor physical balance who find it difficult to maintain their equilibrium while donning drawers of the usual construction by first inserting one leg and then 20 the other. In fact, this garment may be donned and adjusted in sitting posture.

Having thus described my invention, I claim as new and desire to secure by Letters Patent:

25 1. A substantially flat ladies' undergarment adapted to be wrapped about the body of the wearer by a horizontal enveloping motion, comprising a camisole portion, a drawer portion, an elastic waist band between said camisole and drawer portions, and means for detachably fastening the free side edges of said undergarment together.

30 2. A ladies' undergarment adapted to be opened out sidewise to form a substantially flat surface wider at the hips than at the waist, comprising a front panel, a rear panel substantially similar to said front panel, means for detachably securing said panels together along their side edges, and 35 a tab secured to one of said panels for detachably securing said panels together near the lowermost parts thereof for forming the leg portions of said undergarments, and an elastic band at the waist line of said under-

40 45 garment.

3. A ladies' undergarment adapted to be

opened out sidewise to form a substantially flat surface comprising a camisole portion decreasing in width from the upper edge of said garment to the waist, an elastic waist band, and a drawer portion increasing in width from said waist band to the hip portion of said garment, means for detachably securing the side edges of said garment together, and means for detachably securing two points on the bottom edge of said garment together.

4. An apron like ladies' undergarment approximately trapezoidal in outline and adapted to be opened out sidewise to form 60 a substantially flat surface, two free edges in the periphery of said undergarment, said edges being adapted to be brought together about the body of the wearer by a horizontal enveloping motion to form one of the sides 65 of said undergarment, a camisole portion decreasing in width from the upper edge of said garment to the waist comprising a front panel and a rear panel continuous with and similar to said front panel, an elastic waist 70 band, a drawer portion increasing in width from said waist band to the hip portion of said undergarment comprising a front panel and a rear panel continuous therewith, a rounded bottom edge in said drawers 75 portion having a central notch therein, said undergarment being adapted to be folded about a line passing through the apex of said notch, means extending along said free side edges to a point between said waist band and said bottom edge for detachably securing said side edges together, and a tab secured to said bottom edge between said notch and one of said side edges arranged to be detachably fastened to another point in 80 said bottom edge, whereby leg holes are formed between said tab, the joined side edges and said notch.

ADALINE EMERSON.

Witness:

AARON H. RUBIN.
